UNITED STATES PATENT OFFICE.

ROBERT B. HOLLAND, OF NORTH YAKIMA, WASHINGTON.

PORTABLE NAIL-DISTRIBUTER.

1,221,736.

Specification of Letters Patent.

Patented Apr. 3, 1917.

Application filed November 7, 1916. Serial No. 130,082.

To all whom it may concern:

Be it known that I, ROBERT B. HOLLAND, a citizen of the United States, residing at North Yakima, in the county of Yakima and State of Washington, have invented certain new and useful Improvements in Portable Nail-Distributors; and I do hereby declare the following to be a full, clear, and exact description of the invention, such as will enable others skilled in the art to which it appertains to make and use the same.

This invention relates to nail distributers.

The object of this invention is to provide a nail distributer of this character in which are embodied a carrier, a hopper hingedly secured in the carrier, a chute pivotally associated to the hopper, and means for supporting the lower end of the chute in the carrier and nail supporting guideways connected to the chute and to the supporting means whereby the nails may be fed from the hopper into the guideways and readily and quickly taken therefrom.

A still further object of this invention is to provide a nail distributer of this character and one that can be so constructed as to provide an adjustable chute to accommodate various sizes of nails, tacks or the like, and one that can be packed away in a small receptacle and carried from one place to the other and readily assembled for use, and the hopper so constructed that the nails when placed therein will be fed downwardly into the chute by the jarring of the receptacle during the assembling operation.

A still further object of this invention is to provide a simple, practical and comparatively inexpensive structure and one that can be manufactured and sold at a comparatively small cost.

With these and other objects in view the invention consists in the novel combination and arrangement of parts hereinafter more fully described and set forth in the claims hereto appended.

In the drawings:

Figure 1 is a perspective view of my nail distributer assembled and made in accordance with this invention.

Fig. 2 is a vertical sectional view of the same.

Fig. 3 is a longitudinal sectional view

taken through the receptacle and distributer when in a folded or collapsed position.

Fig. 4 is a sectional view taken on the line 4—4 of Fig. 2.

Fig. 5 is a top plan view of the chute and nail supporting guideways.

Like numerals of reference designate like and corresponding parts in all the figures of the drawings.

Referring more particularly to the drawings, the numeral 1 designates the box which comprises in its construction the upper section 2 and the lower section 3. The lower section 3 comprises the bottom wall 4 and side walls 5 and the front wall 6 and rear wall 7. The upper edges of the side walls 5 are cutaway as at 8, the purpose of which will be hereinafter more fully described.

The upper section 3 comprises the top wall 9, the side walls 10, front wall, 11, and the rear wall 12. The rear wall 12 of the upper section 2 is hingedly secured to the rear wall 7 of the lower section 3 as at 13 and the edges of the side walls 10 are cutaway near their rear ends as at 14 to receive shoulders 15 formed by the cutting away of the upper edges of the side walls 5.

Pivotally secured to the inner face of the side walls 5 of the lower section 3 are the supporting arms 16, their lower ends being pivotally secured to the inner face of the side walls 5 as at 17 and their front edges are provided near their upper ends with the inwardly extending openings 18, which openings are arranged in direct alinement with each other, the purpose of which will be hereinafter more fully set forth.

A pair of links 19 have their ends pivotally secured to the upper ends of the arms 16 as at 20 and their rear ends are pivotally secured to the inner faces of the side walls 10 as at 21 by bolts 22, the inner ends of which are screw threaded as at 23 to receive the wing nuts 24 thereon so that the arms 16 may be adjusted to various angles, the purpose of which will be hereinafter more fully set forth.

A hopper 25 is hingedly secured to the lower inner edge of the front wall 11 of the upper section 2 as at 26 and comprises in its construction the bottom wall 27, the side walls 28, the rear wall 29. The front edge

being fully open as at 30. The extreme front edge of the bottom wall 27 of the hopper 25 is rolled back upon itself as at 31 to provide a hinge receiving barrel, the purpose of which will be more fully hereinafter described.

A rectangular chute 32 comprises a bottom wall 33, and side wall 34, and a front wall 35. The bottom wall 33 of the chute 32 is provided with a series of spaced longitudinally extending guide openings 36, which guide openings define upturned tongue members 37 which are adapted to secure the inverted V-shaped partitions 38 therein. The extreme outer opposite longitudinally extending guide openings 36 have their opposite ends bent back upon themselves and inclined upwardly as at 39 and then extend vertically and parallel with the side walls 34 of the chute member and are arranged in abutting engagement therewith as clearly shown at 40. Secured transversely across the upper edges of the side walls of the chute near the rear end thereof is a metal strap 41, which strap has its opposite ends bent downwardly as at 42 and arranged to abut the exterior of the side walls 34 of the chute to yieldably force the side walls inwardly thus varying the relative size of the guide openings 36. A pair of bolts 42' are arranged to extend vertically through the strap 41 and through the apex of the inverted V-shaped partitions 38 and have their lower ends extending through the bottom walls 33 and secured thereto as at 43. A pair of angle brackets 44 are secured to the bottom wall 33 and side walls 34 of the chute member 32 and have their ends projecting beyond the rear edge 40 of the chute as clearly shown in Fig. 2 of the drawings.

The vertical flanges 45 of the angle brackets 44 are provided with alined openings 46, the purpose of which will be hereinafter more fully described. A second pair of angle brackets 47 are secured by their horizontal flange to the inner face of the bottom walls 33 and are located between the leg portions of the inverted V-shaped partitions 38 and their forward ends extend beyond the rear edge of the chute member 32 as clearly shown at 46' in Fig. 5 of the drawings.

The vertical flanges of the angle brackets 47 are provided with openings which are adapted to aline with the openings 46 of the first mentioned angle brackets 45. An adjusting bar 49 is arranged through the openings 46 and 46' of the angle brackets 44 and 47 and is provided with the screw threaded portions at opposite ends and designated 50. The opposite end of the bar 49 is provided with winged nuts 51 which wing nuts are adapted to abut one face of

the angle brackets 44, the purpose of which will be hereinafter more fully described.

One end of the bar 49 is provided with the wing nut 52 which is adapted to abut the flange 46' of the angle brackets 47, thus it will be understood that upon adjusting 70 the thumb nuts 51 and 52, the sizes of the openings 36 of the chute member 32 may be regulated as clearly shown in Fig. 5 of the drawings.

Secured transversely across the side walls 75 of the chute near the front wall thereof and near the upper edges of the same is a pivot bar 30' which is adapted to extend transversely through the barrel 31 and the front edge of the bottom wall 27 of the hopper 25 thus hingedly securing the chute to the hopper and permitting the contents of the hopper to pass into the chute as clearly shown in Fig. 2 of the drawings.

A plurality of wire guides 53 are secured by one of their ends to the under side of the chute member 32 and extend outwardly therefrom. The guides 53 comprise a plurality of wires 53' which wires are arranged in pairs and have their inner ends diverging 90 outwardly and the extreme ends of the diverging portions bent angularly as at 54 and are secured to the bottom wall of the chute members 33 on opposite sides of the guide openings 36, the diverging portion of the guide wires 53 permitting the nails sliding from the hopper to be readily moved downward into the guideways and suspended therefrom and to remove the nails, it will only be necessary to take the same by the thumb and forefinger and move the same rearwardly out through the diverging portions of the guideways 53 as clearly shown in Fig. 1 of the drawings.

An adjusting bar 54' substantially L-shaped has its longer arm secured to one guidewire of each pair as at 55, and is provided with a slot 56 to permit the end of the other guidewire of each pair to extend through and be slidably arranged therein, a second bar 57 substantially L-shaped and has its longer arm secured to the ends of the free guidewire of each pair and is adapted to slidably engage the outer face of the bar 54 as clearly shown in Fig. 5 of the drawings.

The shorter arms of the L-shaped members 54 and 57 are provided with openings through which is adapted to extend supporting bolt 58. A support bolt 58 is screw threaded and provided with a wing nut 59, the purpose of which will be hereinafter more fully described.

Secured to the inner end of the bar 57 is 125 the short arm 60 which is arranged to receive one end of the supporting bolt 58 therein, and the portion of the bolt located between the shorter arm of the bar 54 and

the arm 60 is surrounded by a coil spring 61 which permits the wing nut 59 to be adjusted on the bolt 58 thus varying the distance between the wires 53 of each pair of guide wires 53, as clearly disclosed in Fig. 5 of the drawings.

Secured to the outer face of one side wall 10 of the upper portion 2 is a handle member 62 which permits the device to be carried when desired. The front wall 6 of the lower section 3 is provided with a stud 63 which coöperates with a hook 64 which is pivotally mounted to the front face of the front wall 11 of the upper section 2 to hold the sections in a closed position.

A spring member 65 has one end rigidly secured as at 66 to the inner face of the rear wall 12 of the upper section and has its forward end extending outwardly and inclined upwardly and downwardly as at 66 to constitute a stop which is adapted to engage the front edge of the chute when the same is swung inwardly into the top section holding the chute against outward movement with relation thereto.

In operation:

The upper section 21 is swung back on its hinges 13 and is arranged at approximately right angles to the lower section 3 thus bringing the rods 16 into a vertical position. The wing nuts 24 are tightened thus holding the upper section 3 in a rigid position. The chute is grasped and pulled outwardly raising the hopper on its hinges 26 and the chute is then swung on its hinge and the ends of the rod 58 and 58' are removably secured in their notches 18 in the front edges of the rods 16. It being understood that the rods 16 can be adjusted by the thumb screws 24 permitting the rods to be arranged at various angles which adjustment will arrange the hopper and chute at various angles. Nails are placed in the hopper and fed downwardly to the chute by jarring the casting, and the nails will then strike the inverted V-shaped partitions 39 and be deflected out through the openings in the bottom walls into the guideways 53. Should the nails not pass into the guideways formed by the wires 53, they will fall into a pan 69 which is located in the bottom section 3 and this pan may be readily lifted therefrom and the nails replaced in the hopper and the operation repeated.

When it is necessary to take the nails from the guideways the operator grasps the nails by the thumb and forefinger and slides the same toward divergent portions of the wires so that the same may be readily removed.

It can be readily understood that the guide openings 36 and wires 53 may be adjusted to compensate for various sizes of nails by the adjustment of the winged nuts 51, 59 and 52.

To collapse the device the guideways 53

are lifted from engagement with the rod 16 and are moved up into contact with the under side of the hopper and the hopper is swung on its hinge 26 until the chute and hopper and guideways are located within the upper section and the edge of the chute has engagement with the stops 66 thus preventing accidental outward movement of the hopper and chute from the upper section. The wing nuts 24 are then unscrewed and the upper section forced downwardly into the lower section and the hook member 64 is fastened around the stud 63 thus locking the upper section against movement with relation to the lower section and the device may be readily carried to the next place of operation.

What is claimed is:

1. A portable nail distributor comprising a sectional receptacle, supporting arms pivotally secured in one section of the receptacle, links pivotally secured to the upper ends of the arms and adjustably secured to the upper section, a hopper hingedly secured to the upper section, a chute carried by the hopper, guideways attached to the chute and having their forward ends associated with the arms, and means for adjusting the arms and chute and hopper to various angled positions.

2. A nail distributor comprising a receptacle including hinged sections, supporting arms pivotally mounted in the lower section, links pivotally connected to the upper ends of the supporting arms and adjustably secured to the upper section, a hopper hingedly secured to the upper section and depending therefrom, a chute hingedly secured to the forward end of the hopper and comprising a plurality of nail guideways each having a flange projecting beyond the nail guiding portion and a rod arranged to extend transversely through the flanges, said rod being arranged to coöperate with the flanges to adjust the width of the guideways.

3. A nail distributor comprising a sectional casing, arms and links pivotally secured to the sectional casing and means for holding the arms and links in various angled positions, a hopper hingedly secured in the casing to one section thereof, a chute, guideways carried by the chute and associated with the arms, and means for adjusting the hopper and chute at various angled positions with relation to one another.

4. A nail distributor comprising a hinged sectional casing, a hopper hingedly secured in the casing, a chute carried by the hopper, a plurality of guideways carried by the chute, and means carried by said casing and coöperating with the guideways for holding the guideways, hopper and chute in various angled positions with relation to one another.

5. A nail distributor comprising a hinged sectional casing including top and bottom sections, a pair of arms pivotally secured by their lower ends to the opposite sides on the inner faces of the lower section, a pair of links having one of their ends pivotally secured to the upper ends of the arms, their free ends adjustably secured to the opposing faces of the side walls of the upper section of the casing, the upper forward front edges of the arms provided with spaced notches, a hopper hingedly secured to the upper section, a chute hingedly secured to the forward edge of the hopper, a plurality of guideways attached to the chute, and means in the free ends of the guideways cooperating with the notches of the arms for holding the chute and hopper in various angled positions with relation to the upper section of the casing.
10. A nail distributor of the class described comprising a hinged casing including top and bottom sections, a pair of vertical arms pivotally secured at their lower ends to the side walls of the bottom section, the forward front edges of the arms provided with a plurality of spaced notches, a pair of links pivotally secured to the opposing faces of the side walls of the top section, their free ends pivotally secured to the upper ends of the arms, means extending through the side walls of the top section and rear ends of the links for supporting the top section at various angles with relation to the bottom section of the casing, a hopper hingedly secured to the front wall of the top section, a chute hingedly secured to the forward or free end of the hopper, a plurality of inverted V-shaped partitions in the chute, a plurality of guideways arranged in pairs and located
- on the underside of said chute and extending forwardly therefrom, a bar connecting the free ends of said guideways, bolts extending transversely through the flanges and adapted to be positioned in the notches in the forward edges of the arms for holding the chute and hopper in various angled positions with relation to the upper section, means for holding the hopper and chute and guideways in the top section when in a collapsed position, and means for holding the top and bottom sections of the casing in a collapsed position.
15. A portable nail distributor comprising a sectional receptacle, supporting arms located in the receptacle, links carried by the arms and receptacle, a hopper hingedly secured to one section of the receptacle, a chute carried by the hopper, guideways formed integrally with the chute, nail guiding extensions on the guideways, and means for adjusting the extensions, said means adapted to support the chute and hopper in various angled positions.
20. A nail distributor comprising a sectional casing, a hopper hingedly secured in the casing, a chute associated with the hopper, said chute provided with a plurality of relatively spaced longitudinally extending slots in its bottom, a strap secured across the side walls of the chute, angled brackets secured to the bottom wall of the chute, means extending through the angled brackets for varying the size of the slots, guideways carried by the chute, and means associated with the guideways for supporting the chute and hopper in various angled positions in one section of the casing.
25. A portable nail distributor comprising a sectional receptacle, supporting arms located in the receptacle, links carried by the arms and receptacle, a hopper hingedly secured to one section of the receptacle, a chute carried by the hopper, guideways formed integrally with the chute, nail guiding extensions on the guideways, and means for adjusting the extensions, said means adapted to support the chute and hopper in various angled positions.
30. A nail distributor comprising a sectional casing, a hopper hingedly secured in the casing, a chute associated with the hopper, said chute provided with a plurality of relatively spaced longitudinally extending slots in its bottom, a strap secured across the side walls of the chute, angled brackets secured to the bottom wall of the chute, means extending through the angled brackets for varying the size of the slots, guideways carried by the chute, and means associated with the guideways for supporting the chute and hopper in various angled positions in one section of the casing.
35. A nail distributor comprising a sectional casing, a hopper hingedly secured in the casing, a chute associated with the hopper, said chute provided with a plurality of relatively spaced longitudinally extending slots in its bottom, a strap secured across the side walls of the chute, angled brackets secured to the bottom wall of the chute, means extending through the angled brackets for varying the size of the slots, guideways carried by the chute, and means associated with the guideways for supporting the chute and hopper in various angled positions in one section of the casing.
40. A nail distributor comprising a sectional casing, a hopper hingedly secured in the casing, a chute associated with the hopper, said chute provided with a plurality of relatively spaced longitudinally extending slots in its bottom, a strap secured across the side walls of the chute, angled brackets secured to the bottom wall of the chute, means extending through the angled brackets for varying the size of the slots, guideways carried by the chute, and means associated with the guideways for supporting the chute and hopper in various angled positions in one section of the casing.

Copies of this patent may be obtained for five cents each, by addressing the "Commissioner of Patents, Washington, D. C."

In testimony whereof I affix my signature.
ROBERT B. HOLLAND.
